MILK PAIL COVER AND FASTENER
THEREFOR

Frank W. Moore, Lennen, Mich.

Application March 3, 1936, Serial No. 66,941

4 Claims. (Cl. 220—58)

This invention relates to an improvement in milk pails and more particularly relates to an improved means for securely but detachably holding the cover in place upon the pail.

One object of the invention is to provide a device of this character wherein the fasteners for holding the cover upon the milk pail are formed from portions struck from ears of handle-engaging brackets carried by the pail, thus providing fasteners which will be firmly mounted at opposite sides of the pail and will not add to the cost as they are formed from portions of the brackets ordinarily cut out and thrown away to form handle-engaging portions.

Another object of the invention is to so form the cover engaging fasteners that while the cover may be easily slid into or out of position upon the pail to dispose marginal portions of the cover under the fasteners, it will be securely held when engaged by the fasteners and prevented from accidentally slipping out of its proper position upon the pail.

The invention is illustrated in the accompanying drawing, wherein

Figure 1 is a view showing a pail and its cover in top plan, the cover being secured in place upon the pail by fasteners of the improved construction.

Figure 2 is a view showing the pail and cover partially in side elevation and partially in vertical section along the line 2—2 of Figure 1.

Figure 3 is a fragmentary view upon an enlarged scale taken along the line 3—3 of Figure 1.

Figure 4 is a fragmentary sectional view taken through the marginal portion of the cover before the cover is applied to the pail.

Figure 5 is a fragmentary top plan view illustrating a fastener of a slightly modified construction.

Figure 6 is a view similar to Figure 4 showing another modified construction.

The milk pail, which is indicated in general by the numeral 1, is of a conventional construction and at opposite sides carries brackets 2 with which eyes 3 at ends of the handle 4 are connected. Each of the brackets 2 is formed from a blank of strong sheet metal which is substantially T-shape to provide an attaching portion or base 5 which bears against the outer face 50 of the milk pail and is firmly secured against the same under the bead 6 by rivets or equivalent fasteners 7. The arm or shank of the bracket is bent outwardly for close contacting engagement with the under face of the bead and then upwardly to provide an ear 9 which projects

above the bead at the outer edge thereof, and referring to Figures 2 and 3 it will be seen that this ear has its intermediate portion cut to form a tongue 10 which instead of being entirely cut free from the ear is left attached at its lower end and is bent inwardly to dispose it in overhanging relation to the bead of the pail. Therefore, an ear of an inverted U-shape will be provided at each side of the pail and the eyes 3 of the handle may be engaged through the ears, as shown clearly in Figure 2, to loosely mount the handle and permit it to be disposed either in a carrying position above the pail diametrically thereof or in a lowered position against the pail. The tongues 10 constitute yieldable fasteners for holding the cover 11 in place as the brackets are formed of resilient metal. This cover has a flat marginal portion 12 which surrounds the dome-shaped portion 13 and is set off from the dome-shaped portion by a bead 14. As the marginal edge 15 of the cover is arcuate, as shown in Figure 1, a portion of the pail will not be closed when the cover is in place and the pail may be used for milking with the cover in place. At diametrically opposed points the marginal portion 12 of the cover has portions pressed upwardly to form bowed portions 12' and within these bowed portions are stamped lugs 16 which extend radially of the cover and are arcuate in cross section, as shown clearly in Figure 3. In view of the fact that the lugs 16 are arcuate in cross section and are carried by upwardly bowed portions 12', the cover may be applied to the top of the milk pail where it will rest upon the bead 6 and when pressure is applied to slide it across the pail, the cover may be forced into the position shown in Figure 1 as edges of the tongues 10 will engage the curved surfaces of the bowed portion and the lugs and thus be sprung upwardly until the lugs have moved into place under correspondingly shaped seats 17 formed by pressing portions of the tongues upwardly. The bent portions of the tongues forming the seats 17 extend downwardly along the brackets, as shown at 17', and strengthen the tongues at their junction with the brackets. As soon as the lugs reach a position in which they are disposed under the seats, the resiliency of the tongues will move them downwardly to the position shown in Figure 3 wherein in each lug 16 fits snugly into the seat or socket 17 of a companion tongue and marginal portions of the tongue rest upon the upper face of the marginal portion of the cover. The bowed portions 12' of the cover will be flattened when the cover is in place and their resiliency will aid in 55

maintaining the lugs in the seats. The cover will thus be prevented from slipping circumferentially or diametrically of the milk pail out of its proper position. When, however, it is desired to remove the cover, it is merely necessary to apply pressure and exert sufficient force to spring the tongues 10 upwardly to such an extent that the lugs 16 can move out of the seats 17 and the entire cover shifted along the bead 6 of the pail to a position in which it may be removed. It will thus be seen that the resilient fasteners for the cover may be formed as an integral part of the bracket carrying the handle and auxiliary fasteners for the cover need not be provided.

In Figure 5 there has been shown a slightly modified construction wherein the seat 18 is hemispherical in shape instead of being elongated radially of the milk pail and, of course, the marginal portions of the cover will be formed with upstanding lugs corresponding in shape to the lug receiving seats of the tongues or latches carried by the brackets. It should also be noted that instead of providing the cover with a single lug at each side, the marginal portion of the cover may be formed at each side with a pair of hemispherical lugs 19 spaced from each other a distance substantially corresponding to the width of the tongues 10, as shown in Figure 6. When this embodiment of the invention is used, the tongues are each disposed between a pair of lugs when the cover is in place and it is not necessary to provide the tongue with a lug receiving seat. This is due to the fact that the cover is held in place by engagement of the lugs 19 with opposite side edges of the tongues instead of providing interengaging lugs and seats upon the cover and tongues.

Having thus described the invention, what is claimed as new is:

1. A receptacle open at its top, brackets at opposite sides of the receptacle formed of resilient material and each having a base portion rigidly secured against the receptacle and an arm extending upwardly from its base portion and projecting above the receptacle, a tongue struck from the arm of each bracket with its lower end integrally united to the arm, the tongues being bent inwardly and downwardly to provide inverted U-shaped ears of the marginal portions of the arms and when bent downwardly providing resilient securing tongues overlying marginal edges of the receptacle in vertical spaced relation thereto, a bail having its ends formed with eyes engaged with the ears, and a cover resting upon the upper marginal edge of the receptacle and slid horizontally into place to dispose the

tongues in overlying relation to opposed marginal portions of the cover, the said marginal portions of the cover being provided with upstanding lugs and said tongues being provided with seats receiving said lugs and frictionally gripping the same to securely but detachably hold the cover in place. 5

2. A receptacle open at its top, brackets of resilient material carried by the receptacle at opposite sides thereof and having ears projecting upwardly from the receptacle and resilient 10 tongues extending inwardly from the brackets at lower ends of the ears in overlying relation to the upper marginal edge of the receptacle, a bail having its end portions engaged with said ears, and a cover resting upon the upper marginal edge 15 of said receptacle and slid horizontally into place to dispose the tongues in overlapping relation to opposed marginal portions of the cover, the tongues and overlapped portions of the cover having portions offset to form seats and companion lugs engageable in the seats to securely but detachably hold the cover in place upon the receptacle. 20

3. A receptacle open at its top, ears projecting upwardly from the receptacle at opposite sides thereof, resilient tongues extending from said ears inwardly of the receptacle in overlying and vertical spaced relation to the upper marginal edge of the receptacle, a bail having its ends connected with said ears, and a cover resting upon the upper marginal edge of the receptacle and slid horizontally into place to dispose opposed marginal edge portions of the cover under the tongues, each tongue and the cooperating marginal portion of the cover overlapped thereby 35 being provided one with a seat and the other with a member snapped into the seat during movement of the cover into place, whereby resiliency of the tongues causes the said members to be gripped and the cover securely but removable held in place. 40

4. A receptacle open at its top, ears projecting upwardly from the receptacle at opposite sides thereof, a bail having its ends connected with said ears, resilient tongues extending from said ears inwardly of the receptacle in overlying relation to the upper marginal edge of the receptacle and each having a portion projected upwardly to form a seat in its under face, and a cover resting upon the receptacle and slid into place to dispose marginal portions of the cover under the tongues, the portions of the cover overlapped by the ears having portions projected upwardly to form lugs for engaging in the seats of the tongues and securely but detachably hold 55 the cover in place. 50
